Attorney.

UNITED STATES PATENT OFFICE.

SANFORD E. WEST, OF PAWTUCKET, RHODE ISLAND.

GARMENT-SUPPORTER.

No. 868,899.

Specification of Letters Patent.

Patented Oct. 22, 1907.

Application filed March 25, 1907. Serial No. 364,542.

To all whom it may concern:

Be it known that I, SANFORD E. WEST, a citizen of the United States, and a resident of the city of Pawtucket, in the county of Providence, State of Rhode Island, have invented certain new and useful Improvements in Garment-Supporters, of which the following is a specification.

My invention relates to a device for connecting to suspenders and having means to clasp upon the girth-hem of a trousers and drawers, thus dispensing with the common button and tape connection on said garments, and providing a device which shall be more convenient to use and of lesser liability to get out of order than the devices now generally used for this purpose.

In the accompanying sheet of drawings, Figure 1 represents an edge view of my improved garment clasp, as in open condition. Fig. 2 is a rear view of the same. Fig. 3 is a central vertical sectional view, showing the suspender-connection to the clasp and the latter in closed condition upon the girth-hem of a trousers and drawers, and, Figs. 4, 5 and 6 represent rear perspective views of the structural parts of my device.

Like reference characters indicate like parts throughout the several views.

My improved garment supporter comprises three vertically arranged members *a*, *b* and *c*, which are made from sheet metal. The member *a* has its longitudinal edges curved inwardly to form guide-ways *a*¹, *a*², to receive the member *b*. The upper portion of the member *a* is curved outwardly to form a hook *a*² for connection with the slit *r* of the suspender *s*. Between the guide-ways *a*¹ the metal is upset to form a longitudinal groove *a*³, to receive the indentation *b*¹ formed in the member *b*, and arranged to limit the sliding movement of the member *a* upon said latter member. The member *b* has two laterally extending circular bent portions *b*², *b*³, to receive therethrough a pin *p*. The member *c* is slotted longitudinally so as to leave a central strip *c*¹ whose upper portion is provided with a lateral depression *c*² for the pin *p* to rest against in securing said member *c* to the member *b*. The upper portion of the member *c*, above its depression *c*², is curved to form a

tongue *c*³, to bear against the rear surface of the member *a* in closing the hinged members *b* and *c*. Each member *b* and *c* is provided with a series of upset prongs *d*, *d*¹ which extend toward each other, as shown.

The operation of the device is as follows: Assuming the clasp to be open and in position over the hems of the garments *e* and *f*, as shown in Fig. 1, a thumb pressure is exerted upon the tongue *c*³ to shove downward 50 the hinged gripping-members *b*, *c*, and as the tongue comes into frictional contact with the member *a* it causes the prongs of both members *b*, *c* to firmly embed against the hems of the garments, in the manner shown in Fig. 3.

The releasing of the device is accomplished by exerting an upward pressure upon the lower edge of the gripping member *c*, and a downward pressure upon the hook portion *a*². This causes a relative movement between the gripping members and the hook member, 60 which effects the releasing of the garment edge from the bight of the gripping members.

By my construction and arrangement of parts, I provide a clasp that may be quickly and easily applied to support two garments, and at the same time a clasp that 65 is simple and inexpensive to manufacture.

What I claim and desire to secure by Letters-Patent, is—

A garment-supporting device comprising in combination a hook-member having oppositely disposed guide-ways; a 70 prong-gripping-member slidably mounted in the guide-ways of the first said member and having two laterally disposed circular bent portions; a pin secured through the bent portions of said gripping-member; a second prong-gripping-member having a central strip formed by slitting 75 the metal, the strip being provided with a lateral depression for said pin to rest upon in securing both gripping-members together, and the last mentioned gripping member having a tongue which coming in contact with the hook-member causes the gripping-members to be held in a firmly closed 80 condition.

In testimony whereof I affix my signature in presence of two witnesses.

SANFORD E. WEST.
